J. NUTRY

NOVELTY CONTAINER

Filed April 8, 1922

Patented Mar. 24, 1925.

1,530,908

UNITED STATES PATENT OFFICE.

JOHN NUTRY, OF RIDGEWOOD, NEW JERSEY.

NOVELTY CONTAINER.

Application filed April 8, 1922. Serial No. 550,587.

To all whom it may concern:

Be it known that I, JOHN NUTRY, a citizen of the United States, residing at Ridgewood, in the county of Bergen and State of New Jersey, have invented certain new and useful improvements in Novelty Containers, of which the following is a specification.

This invention relates to a novelty container, and an object of the invention is to provide a container which resembles a book in outward appearance but which may be used for a bank or for other similar purposes, and which may be produced in an attractive form at small expense.

A more detailed object is to provide a container as indicated made up of a body part and opposite cover parts, of substantially identical construction, pivotally connected with the body and adapted to be locked in closed position by a single key controlled lock mechanism comprised in the body.

A further object is to provide for simple and substantial construction of all of the parts so that they may be produced and assembled at small expense.

Other objects and aims of the invention, more or less specific than those referred to above, will be in part obvious and in part pointed out in the course of the following description of the elements, combinations, arrangements of parts and applications of principles constituting the invention, and the scope of protection contemplated will be indicated in the appended claims.

In the accompanying drawings which are to be taken as a part of this specification, and in which I have shown merely a preferred form of embodiment of the invention:—

Figure 1 is a perspective view of a container constructed in accordance with this invention, the opposite cover parts thereof being shown in open position.

Figure 2 is a plan view of the container, being shown partly in central section for the disclosure of details,

Figure 3 is a transverse sectional view, partly in elevation,

Figure 4 is a diagrammatic view illustrating the construction and operation of the lock mechanism employed, and

Figure 5 is a fragmentary detail view illustrating an interlocking arrangement of parts at the hinge points.

Referring to the drawing for describing in detail the structure which is illustrated therein, the reference character L indicates the body, while the reference characters G and H indicate respectively the two cover parts which are hinged to the body and which, when in closed position, fit against the open sides, being designed preferably so as to give the exterior appearance of a book.

The body L consists of a strip of sheet metal bent into U shape providing the two legs 1 and 2, and the connecting portion 3. The legs 1 and 2 are adapted to constitute the end leaf-edge portion of the container, while the connecting portion 3 is adapted to constitute the front leaf-edge portion of the container.

The ends of the legs 1 and 2 are formed with flanges 4 and 5 which are apertured to receive tangs 6 by which they are connected with a separately formed metallic back strip 7, said back strip thus serving to hold the legs 1 and 2 in proper relation to each other for forming a substantially rigid rectangular structure.

The parts 1, 2 and 3 may be formed with edge flanges 8, if desired, for strengthening and ornamental purposes.

A channel-shaped strip 9 is carried at the inner side of the portion 3 of the body disposed to provide a chamber 10 for containing a suitable lock mechanism, indicated generally by the reference character 11. This lock mechanism may take any appropriate form but preferably comprises two pairs of movable latch members 12 and 13 under the control of a single key, as 14, which is adapted to be inserted into a key-hole 15 formed thru the portion 3 for operating said mechanism.

A suggested form of lock mechanism for this purpose is shown herein in Fig. 4, and described in my copending application, Serial No. 555,469.

The covers G and H consist each of an outer layer 16 of ornamental cloth, leather, or the like, a filler 17 of soft card board, or the like, a sheet metal stiffening plate 18 and sealing plate 19. The edge portions as 20, of the covering material 16 are folded inwardly about the edge portions of the filler 17 and stiffening plate 18 and are pasted to the inner surface of the stiffening plate. Thereafter the sealing plate is arranged to cover and conceal the margins of

the portions 20 and is held firmly in position by tangs 21 which are struck up from the stiffening plate and which extend thru mating apertures formed in the sealing plate.

As has been before suggested, both of the covers are identical. The tools, dies, etc., employed for the production of one serves also to produce the other so that thus a very great saving in cost is possible.

As a simple and inexpensive expedient for connecting the covers with the body the drawing herewith shows the filler 17 and the covering material 18 to extend continuous from one cover to the other across the outer surface of the back member 7 of the body so that portions, as 22, of these elements serve as connecting hinges for the covers. It is noted particularly in this connection that the inturned portions 20 of the covering material extend across the inner surface of the back member 7, as at 23, and between said inner surface and the opposing surfaces of the flanges 5, also that the tangs 6, which project from the member 7 for fastening the flanges 5 to said member 7, extend thru said portions 23.

The portions 23 are thus made to serve as covering for the extending ends of the back member 7, and the bond thus produced between the two covers and the body is made at once very cheap to manufacture, wholly pleasing in appearance, and thoroughly efficient in use.

Each of the sealing plates 19 has marginal flanges 24 and 25 at opposite ends and a marginal flange 26 at one side. These flanges are disposed so that when the covers are closed said flanges fit closely within the open space defined by the flanges 8 of the body so as thus to provide a suitable seal against possible egress of coins, or other articles, thru the cracks between the body and the covers.

Portions of the flanges 26 of the sealing plates are provided to form latch lugs 27 which are disposed to cooperate with the latch members 12 and 13 of the lock mechanism. Each of the lugs 27 is shaped to provide an undercut groove 28 into which the latch members engage when the covers are closed.

When the cover H is closed, the two latch lugs carried thereby interengage with one pair of latch members, as 12, of the body.

When the cover G is closed the lugs 27 thereof interengage with the other pair, as 13, of the latch members of the body.

Rotation of the key 14 within the key-hole 15 will simultaneously release both pairs of latch members 12 and 13 and permit opening of the two covers.

The body may, if desired, be formed with a suitable money slot, as 29.

It will be apparent that altho the hinge

parts 22 described may serve their purpose very efficiently, nevertheless since they are formed only of card board and fabric a maliciously inclined person might readily open the container by severing the hinge 70 parts with an ordinary pocket knife, or the like. To forestall this possibility it is proposed, as indicated in Fig. 5, that the sealing plates 19 be formed with an out-standing flange part 30, disposed so that when the 75 covers are being moved to closed position, said flange parts will engage behind up-standing flange parts 31 formed at the longitudinal edges of the back member 7.

A solid metallic connection is thus provided which will prevent possibility of opening the covers without releasing the lock mechanism heretofore described.

As many changes could be made in this construction without departing from the scope of the invention as defined in the following claims, it is intended that all matter contained in the above description, or shown in the accompanying drawings, shall be interpreted as illustrative only and not in a 90 limiting sense.

Having thus described my invention, what I claim as new and desire to secure by Letters Patent is:—

1. A novelty container comprising a body part open at both sides and including a back member, a pair of covers one at each side of the body, covering material for the covers extending from cover to cover across the outer surface of said back member and constituting hinge parts for connecting the covers with the body, said covering material having marginal portions turned inwardly at the inner sides of the covers and being continuous across the inner surface of said back member to thus reinforce the hinge connection between the covers and the body, and means whereby said covers may be held closed when desired.

2. A novelty container comprising a body part open at both sides and including a back member, a pair of covers one at each side of the body, covering material for the covers extending from cover to cover across the outer surface of said back member and constituting hinge parts for connecting the covers with the body, said covering material having marginal portions turned inwardly at the inner sides of the covers and being continuous across the inner surface of said back member to thus reinforce the hinge connection between the covers and the body, the body member having parts disposed to lie parallel with the inner surface of said back member, said last mentioned portions of the covering material being interposed between the inner surface of said back member and said mentioned parts of the body, and tangs extending thru the interposed portions of the covering material between said

back member and the mentioned portions of the body for fastening the body to the back member and thereby clamping said interposed portions of the covering material 5 against disconnection.

3. A novelty container comprising a body part open at both sides, a pair of covers one at each side of the body, means pivotally connecting said covers with the body, each 10 cover comprising a stiffening plate at its inner side, covering material for said plate being folded inwardly about the margins of the plate, sealing plates one for each cover being arranged one at the inner surface of 15 each stiffening plate disposed to overlap the inner edges of the covering material, means interengaging between the stiffening plates and the sealing plates to hold said parts assembled, and the sealing plates having latch 20 parts comprised therein adapted to interengage with parts of the body for holding the covers closed.

4. A novelty container comprising a body part open at both sides and including a 25 metallic back member, a pair of covers one at each side of the body, fabric covering material for the covers extending from cover to cover across said back member and constituting hinge parts for connecting the

covers with the body, metallic plates carried 30 by each of said covers having parts arranged to interengage with the metallic back of the body when the cover is closed for thereby forming a metallic interlock between the covers and the body adjacent the hinges, 35 together with releasable means to retain the free end of the covers closed.

5. A novelty container comprising a body part open at both sides, a pair of covers one at each side of the body, each cover comprising 40 an interior stiffening plate, an exterior covering of fabric, and a filler the stiffening plates of the two covers being formed separate from each other and from the body, but the filler and the covering material of the two covers being continuous from one cover to the other across a part of the body and serving thereby to constitute hinges for connecting the covers with the body, together with releasable means to retain 45 the free edges of the covers closed.

In testimony whereof I affix my signature in the presence of two witnesses.

JOHN NUTRY.
